(57) **CLAIM**

The ornamental design for a display mounting bracket for a video conference system endpoint, as shown and described.

DESCRIPTION

FIG. 1 is a front, right perspective view from above of a display mounting bracket for a video conference system endpoint according to the present invention;

FIG. 2 is a front, right perspective view from above of the display mounting bracket of FIG. 1 where the display mounting bracket is shown in a bent mounting configuration;

FIG. 3 is front, right perspective view from above of the display mounting bracket of FIG. 1 where the display mounting bracket is shown in another bent mounting configuration;

FIG. 4 is front, right perspective view from above of the display mounting bracket of FIG. 1 where the display mounting bracket is shown in a still other bent mounting configuration;

FIG. 5 is a top plan view of the display mounting bracket of FIG. 1;

FIG. 6 is a bottom plan view of the display mounting bracket of FIG. 1;

FIG. 7 is a front elevation view of the display mounting bracket of FIG. 1;

FIG. 8 is a rear elevation view of the display mounting bracket of FIG. 1;

FIG. 9 is a right side elevation view of the display mounting bracket of FIG. 1; and

FIG. 10 is a left side elevation view of the display mounting bracket of FIG. 1; and,

FIG. 11 is a front, left perspective view of the display mounting bracket shown in use with a video display and a video conference system endpoint.

Any portions shown in phantom are for illustrative purposes only and form no part of the claimed design.
